UNITED STATES PATENT OFFICE.

ROBERT W. THURMAN, OF LYNCHBURG, VIRGINIA.

REMOVABLE PERMUTATION-LOCK.

SPECIFICATION forming part of Letters Patent No. 257,626, dated May 9, 1882.

Application filed March 16, 1882. (No model.)

To all whom it may concern:

Be it known that I, ROBERT W. THURMAN, a citizen of the United States of America, residing at Lynchburg, in the county of Campbell and State of Virginia, have invented certain new and useful Improvements in Removable Permutation-Locks; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

The object of my present invention (which is an improvement on my former Patent No. 252,336) is to secure a permutation-lock in the door to which it is to be applied in a manner so strong and simple that while offering great resistance to attempts at dislodgment it may readily be removed by the employment of devices arranged for that purpose.

In the accompanying drawings, in which similar letters of reference indicate corresponding parts, Figure 1 is a front view of a portion of a door from which my lock has been removed. Fig. 2 is a side view of my lock-case, showing means for securing it in position, and a partial view of the contained locks visible through the broken-away portions. Fig. 3 is a section on line *y y*, Fig. 2.

In the drawings, *A A'* represent a cylindrical shell or case of metal, preferably constructed in two parts secured together, the front piece or part being somewhat larger in diameter than the rear, and formed with the screw-thread *G'* on its outside. Each of these two parts contains a separate and distinct permutation-lock. The tumblers *h* of lock *N* are circular, and are formed with the notches *h'* in their outer edge. The tumblers of lock *O* are of any known style that are circular in form. The spindles of both these locks are brought to the front end of the case, the spindle of the forward or secondary lock, *N*, being made hollow to permit the spindle *B* of the rear lock to be operated through it as though it were not there.

On the outer end of spindle *B* is the ordinary dial, *D*, operating as usual. Underneath,

concealed by dial *D*, is a smaller dial, *S*, for operating the secondary lock *N*, which is otherwise unaffected by the ordinary operation, in the usual manner, of lock *O*. There is a slot, *F*, in the case *A A'*, extending as far forward as the last of the second set of tumblers, and of about the same width as the notches in the tumblers. This slot may be made in two portions in different parts of the case, but is preferably placed as shown. That portion of slot *F* in the rear and smaller portion, *A'*, of the case is for the door-bolts to slide into when the combination is set up and the door ready to be opened.

In the slotted portion of *A* moves the free end of pawl *C*, which is pivoted in another and smaller slot, *C'*, extending up to slot *F*. The spring *H* is attached to pawl *C* near its pivotal point and holds it down. In the front end of cylinder *A* are formed holes, in which may be fixed the pins *q*, by the application of any flat instrument to which, or of a wrench adapted to engage with the said holes, the pins being removed, the case *A A'* may be manipulated.

In the orifice *E'* of the door is secured a sleeve, *E*, provided on its inner surface with a female screw, *G*, coinciding with screw-thread *G'* on the case *A*. This sleeve *E* is secured to the door by flange on its inner edge. In the female screw *G* is cut a groove, *F'*, coinciding with groove *F* and pawl *C* of cylinder *A*.

A safe, vault, or other door has an aperture in which the sleeve *E* is secured. The combination of lock *N* is set up and the pawl *C* is pressed by spring *H* into the notches thereof. In that condition the case *A A'* is, by the aid of a wrench or flat bar and pins, screwed into the door, and when in position, by dogging the tumblers of lock *N* the pawl *C* is thrown up into groove *F'*, preventing the further turning of case *A A'* and securing it in its place. When the lock is in place and the combination of lock *O* is set up through dial *D* the door-bolts will slip into the notches therein, and in so doing the door will be unlocked.

It will be seen from the foregoing that the secondary lock *N*, by means of which and its accessories the whole is secured in the door, is only intended for use should the ordinary lock, *O*, controlling the bolt-work, fail to operate, in

which case, by unlocking the lock N, the case A A' may be unscrewed from the door and repaired or replaced.

Having described my invention, what I claim, 5 and desire to secure by Letters Patent, is—

1. The locks N O and cylindrical case A A', formed with screw-thread G thereon and slot F therein, in combination with pawl C and spring H, arranged to operate as and for the 10 purpose specified.
2. A removable lock consisting of slotted screw-threaded case A A', pawl C, and spring

H, in combination with locks N O, spindles B b, dials D S, and indented notched tumblers h, arranged to engage with the coincident screw-thread and groove of sleeve E, as shown and described. 15

In testimony whereof I affix my signature in presence of two witnesses.

ROBERT W. THURMAN.
